BAR STOOL

Merle C. Melchior, Los Angeles, Calif., assignor of one-half to Sidney Galper, Los Angeles, Calif.

Filed Sept. 29, 1964, Ser. No. 81,908

Term of patent 14 years

(Cl. D15—8)

I claim:

The ornamental design for a bar stool, substantially as shown.
